YARN WINDING DEVICE

Richard R. Almy, Warwick, R. I., assignor to E. I. du Pont de Nemours & Company, Wilmington, Del., a corporation of Delaware

Application September 7, 1940, Serial No. 355,725

6 Claims. (Cl. 91—51)

The present invention relates to apparatus for the winding of yarn into a package, and more particularly, it relates to the winding of yarn and the simultaneous application of oil or other treating or finishing liquid, in a satisfactory, uniform manner to the yarn.

In the winding of yarn on to a cone it is customary to condition or lubricate the yarn during the winding operation in order to improve the running qualities of the yarn, or to impart a softness and pliability to the yarn to enable it to be used in weaving and knitting operations.

In a winding apparatus, the core, or yarn support, is frequently mounted upon a spindle that is driven at a constant speed throughout the entire winding operation. Hence, the linear speed of the yarn being wound upon the cone increases as the package increases in diameter. The increase in the speed of the yarn from the start to the finish of the winding operation is dependent upon the size of the yarn package formed and, in some cases, the speed increases as much as 400%, or even more. Thus, to apply the oil or other finishing composition uniformly to all parts of the yarn being wound upon the cone, it is necessary to adjust the rate of application of the oil so as to compensate for the increase in linear speed of the yarn.

It is therefore an object of the present invention to provide an improved winding and oil applying apparatus whereby the quantity of the oil applied per unit length of the yarn will remain substantially constant throughout the winding operation.

Other objects of the invention will appear hereinafter.

The objects of the invention are accomplished, in general, by pulling the yarn from a fixed yarn supply package over one end of said package thereby causing the yarn to balloon as it passes from the package. The yarn is then passed over an oil wiping roller positioned in the path of the yarn and means are provided for varying the magnitude of the balloon of the yarn so that the yarn will shift over the surface of the wiping roller to varying degrees, dependent upon the linear speed of the yarn.

The present invention will be more readily understood by reference to the following written description when taken in connection with the accompanying illustrations in which:

Figure 1 is a diagrammatic, side elevational view of a winding apparatus constructed in accordance with the present invention.

Figure 2 is an enlarged side elevational view

of a portion of the apparatus shown in Figure 1.

Figure 3 is a sectional view taken along the line 3—3 of a portion of the apparatus shown in Figure 1.

Figure 4 is a top plan view of the oiling roller and yarn guiding mechanism shown in Figure 1.

Referring to the drawings, reference numeral 11 designates a fixed yarn supply package. The yarn 13 is drawn from the top end of the supply package 11 and is passed upwardly to the yarn support 35 which is positioned on the winding spindle 36. A slotted yarn guide 15 is positioned a short distance from the top of the supply package 11. A movable yarn restraining guide 17 is positioned a slight distance above slotted yarn guide 15. The restraining guide 17 is provided with two legs 17A which pass through a U shaped supporting member 19. The legs 17A are adapted to reciprocate in the support 19 so as to lengthen and shorten the transverse movement of the yarn due to the ballooning thereof. The yarn is then passed in contact with an oil wiping roller 25. The yarn is maintained in contact with wiping roller 25 by means of rods 21 and 23 spaced a short distance from the periphery of the roller. The yarn then passes upwardly through a convergence guide 27, thence through a yarn tensioning device 29, and from there over a yarn bale guide 31, through reciprocating button guide 33 which guides the thread on to the yarn support 35. The support 35 is rotated by means of rotating spindle 36. The spindle 36 is mounted for rotation in a supporting base 37 of the winding apparatus.

The reciprocating yarn button guide 33 is mounted for reciprocation in the traverse frame back 39. Traverse frame back 39 is counterweighted by means of counterweight 43 and the weight and back are pivoted to the supporting base 37 at 41. The yarn restraining guide 17 is mounted for reciprocating movement in a block 55 which is fixed to the frame of the winding machine. The guide 17 is reciprocated by connection with the counterweight 43 which moves in the direction of the arrow shown thereon as the yarn package increases in diameter. The lever arm 47 is pivoted at 45 to the counterweight 43. The opposite end of lever arm 47 is pivoted at 49 to lever arm 51. Lever arm 51 is pivoted on a fixed pivot 53. The opposite end of arm 51 is pivoted at 57 to the restraining guide 17. The oil wiping roller 25 is positioned for rotation in an oil trough 26.

The above described apparatus functions essentially as follows:

The circular ballooning movement of the yarn as it passes from the yarn supply package 11 is converted into a reciprocating movement by passing through the slotted guide 15. At the beginning of the thread winding operation the legs 17A of the yarn restraining guide 17 project through the support 19 to substantially their entire length. The yarn, as it passes from the slotted guide 15, is held between the restraining guide 17 and the support 19 so that substantially no transverse or side-wise movement of the yarn is permitted. The yarn consequently passes in a constant straight line over the oil wiping roller 25 and to the convergence guide 27. The yarn is maintained in contact with the oil wiping roller 25 by means of rods 21 and 23. The tensioning device 29, which is preferably of the type disclosed in the copending application of Arthur E. Guenther, Serial No. 209,653 filed May 24, 1938, imparts a tension to the yarn so that the latter may be wound on to the yarn support with a uniform tension. The yarn passes from the tensioning member over yarn bale guide 31 and thence is guided on to the package by the button guide 33.

As the wound yarn package increases in diameter (shown in the left hand position of Figure 1) the counterweighted traverse frame back 39 is swung about pivot 41 in the direction of the arrow shown on the counterweight 43. The lever arm 47 is consequently moved to the left and swings lever arm 51 about the pivot 53. As a result the restraining guide 17 is drawn to the right causing the legs 17A of the guide to be withdrawn from the support 19. This will permit the yarn to reciprocate transversely over the surface of the oil wiping roller 25 thereby causing the yarn to pick up a greater quantity of oil due to this sidewise wiping action on the roller. The amount of transverse movement of the yarn over the wiping roller is adjusted to compensate for the increase in linear speed of the yarn so that the quantity of oil actually applied to the yarn will remain constant throughout the winding operation.

Referring to Figure 2 of the drawings, the various parts of the oil wiping mechanism including the restraining guide and the slotted guide 15 are shown on a larger scale than Figure 1. This figure of the drawings is added for the purpose of more clearly visualizing the parts above referred to.

In Figure 3 of the drawings the oil trough 26 is shown in cross-section with the wiping roller submerged in the oil or other finishing liquid. This view of the oiling apparatus shows the path of the yarn as it passes through the slotted guide 15, the restraining guide 17 and under the guide rods 21 and 23. The various parts designated by reference characters in this figure are the same as those above referred to in Figure 1.

Figure 4 of the drawings discloses a top plan view of the oiling mechanism including the restraining guide 17 and the two legs 17A which project through the "U" shaped supporting member 19. The several parts referred to by reference characters in this figure are also the same as those above referred to with reference to Figure 1.

It will be clear that any other type of leverage mechanism commonly employed to transmit a substantially straight-line motion to the movable yarn restraining guide 17 may be employed in place of the particular mechanism disclosed in the drawings and above described. The extent

of motion of the restraining yarn guide 17 is dependent upon the adjustment of the system of leverage members and the present invention contemplates any adjustment of such leverage members that is necessary to permit the desired movement of the movable yarn guide as the yarn package increases in diameter. In the specific mechanism above described use is made of a slotted yarn guide 15 and a restraining guide 17. Obviously, the restraining guide 17 may function both as a slotted guide and restraining guide. It is furthermore believed that the restraining guide need not necessarily have the particular form and construction specifically illustrated and described but may be constructed in numerous modified manners to function substantially in the manner above referred to.

According to the preferred method of operation of the apparatus the oil wiping roller 25 is rotated at a constant speed of from one-fourth to five revolutions per minute. If desired, however, the speed of the roller may be varied as the speed of the yarn increases to pick up an increasingly greater quantity of oil. That is, if the movement of the yarn restraining guide as described above does not sufficiently compensate for the increase in speed of the yarn, satisfactory compensation may be obtained by additionally increasing the speed of the rotation of the roller as the speed of the yarn increases.

Although the invention has been illustrated and described in connection with a winding machine of the type manufactured by the Universal Winding Company, the invention is not limited to this type of winding machine, and may be used to advantage on any type of winding machine in which the yarn is drawn from one end of a stationary supply package, and in which the speed of the yarn increases as the diameter of the wound yarn package increases. By employing the apparatus of the present invention oil, or other treating or finishing composition, may be applied to yarn in a uniform manner throughout the entire winding operation. The apparatus provides means for accurately compensating for the increased speed of the yarn as the wound yarn package increases in diameter.

The most important advantage of the apparatus of the present invention over previous types of oiling and winding mechanism is that it will apply uniform quantities of oil from the start to the finish of the winding operation with the introduction of a relatively small amount of yarn line snubbing angularity. It is well recognized that the impartation of large amounts of snubbing to the yarn will cause the production of "shiners" in the yarn. This is particularly true when the yarn is withdrawn from a package such as a bucket cake where varying tensions are necessary to draw the yarn from the package. A fuller discussion of the disadvantages of yarn snubbing angularity will be found in the co-pending application of Lester S. Sinness, Serial No. 207,587, filed May 12, 1938.

The apparatus of the present invention may be very readily and conveniently threaded because two closed guides which are generally necessary on the conventional slide bar type of compensating oiling device are eliminated. By the use of the apparatus of the present invention yarn may be wound over extended periods of time with a minimum amount of wear on the apparatus, and consequently longer life of the thread guides associated with the oiling mechanism.

Since it is obvious that many changes and modifications can be made in the apparatus specifically described above without departing from the nature and spirit of the invention it is to be understood that the invention is not to be limited to the above described details except as set forth in the appended claims.

I claim:

1. In a yarn winding apparatus of the type in which the speed of the yarn increases as the wound yarn package increases in diameter, a fixed yarn supply package, a convergent guide positioned above said package, means for pulling the yarn from one end of said fixed package thereby causing the yarn to balloon as it passes from said package, an oil wiping roller positioned in the path of the yarn passing between said guide and said supply package, and yarn guide means between said roller and supply package for varying the magnitude of the balloon of the yarn.

2. In a yarn winding apparatus of the type in which the speed of the yarn increases as the wound yarn package increases in diameter, a fixed yarn supply package, a convergence guide positioned above said package, means for pulling the yarn from one end of said fixed package thereby causing the yarn to balloon as it passes from said package, an oil wiping roller positioned in the path of the yarn passing between said guide and said supply package, a slotted yarn guide, and a movable restraining guide between said roller and supply package for converting the circular ballooning movement of the yarn into a transverse shifting motion and for varying the magnitude of said transverse shifting movement of the yarn with said wiping roller.

3. In a yarn winding apparatus in which the speed of the yarn increases as the wound yarn package increases in diameter, a fixed yarn supply package, a convergence guide positioned above said package, means for pulling the yarn from one end of said fixed package thereby causing the yarn to balloon as it passes from said package, an oil wiping roller positioned in the path of the yarn passing between said guide and said supply package, a slotted yarn guide between said supply package and said roller for converting the circular motion of the ballooning yarn to a transverse shifting motion, and a movable restraining guide between said slotted guide and said roller for gradually increasing the transverse shifting motion of the yarn on said roller as the diameter of the wound yarn package increases.

4. In a yarn winding apparatus, a winding spindle, a traverse frame back pivoted to move away from said spindle as the yarn package in-

creases in diameter, a fixed yarn supply package, a convergence guide positioned above said package, said winding spindle pulling the yarn from one end of said fixed package thereby causing the yarn to balloon as it passes from said package, an oil wiping roller positioned in the path of the yarn passing between said guide and said supply package, guide means between said roller and supply package for converting the circular ballooning movement of the yarn to a transverse shifting motion, and a restraining guide means operatively connected to said traverse frame back for gradually increasing the transverse shifting motion of the yarn on the roller as the yarn speed increases.

5. In a yarn winding apparatus, a winding spindle, a traverse frame back pivoted to move away from said spindle as the yarn package increases in diameter, a fixed yarn supply package, a convergence guide positioned above said package, said winding spindle pulling the yarn from one end of said fixed package thereby causing the yarn to balloon as it passes from said package, an oil wiping roller positioned in the path of the yarn passing between said guide and said supply package, guide means between said roller and supply package for converting the circular ballooning movement of the yarn to a transverse shifting motion, a movable yarn restraining guide between said roller and said supply package, and means for connecting said guide to said traverse frame back whereby gradual movement of the traverse frame back will gradually move said guide to increase the transverse shifting movement of the yarn on said roller.

6. In a yarn winding apparatus, a winding spindle, a traverse frame back pivoted to move away from said spindle as the yarn package increases in diameter, a fixed yarn supply package, a convergence guide positioned above said package, said winding spindle pulling the yarn from one end of said fixed package thereby causing the yarn to balloon as it passes from said package, an oil wiping roller positioned in the path of the yarn passing between said guide and said supply package, a slotted yarn guide between said supply package and said roller for transforming the circular motion of the ballooning yarn to a transverse shifting motion, a movable restraining guide between said slotted guide and said roller, means connecting said restraining guide to said traverse frame back whereby gradual movement of the traverse frame back will gradually move said restraining guide to increase the magnitude of the transverse shifting motion of the yarn on said roller.

RICHARD R. ALMY.
